UNITED STATES PATENT OFFICE.

LEBBEUS B. MILLER, OF ELIZABETH, NEW JERSEY, ASSIGNOR TO THE
SINGER MANUFACTURING COMPANY OF NEW JERSEY.

DESIGN FOR A SIDE FRAME FOR SEWING-MACHINE STANDS.

SPECIFICATION forming part of Design No. 16,378, dated November 10, 1885.

Application filed October 13, 1885. Serial No. 179,920. Term of patent 14 years.

To all whom it may concern:

Be it known that I, LEBBEUS BALDWIN MILLER, a citizen of the United States, residing at Elizabeth, in the county of Union and State of New Jersey, have invented and produced a certain new and original Design for the Legs or Side Frame of Sewing-Machine Stands, of which the following is a specification, reference being had therein to the accompanying photographic illustration of my invention.

The leading feature of my design is an oval figure at the lower part of the leg or side frame of a sewing-machine stand, said figure resting on the lower cross-bar of said frame, and being connected with the side and top bars thereof by straight horizontal and vertical bars, the vertical bar being in turn joined to the side bars between the oval figure and the top cross-bar by curved cross-bars.

In the accompanying illustration, which represents my newly-designed leg or side frame in elevation, A denotes the curved outer side bars, which are connected at their tops by a straight cross-bar, B, and at their bottoms by a doubly-curved cross-bar, C, the form of the latter being like a printer's brace. At the lower part of the leg, and resting on the lower cross-bar, C, is an oval figure, D, within which may be placed any appropriate design or lettering. In the present instance the regular trade-mark of the Singer Manufacturing Company is shown as occupying the space within said oval figure; but said trade-mark is not a novel feature of my design, and is not herein claimed. The oval figure D is joined

to the side bars, A, by short straight horizontal bars E, and to the top cross-bar, B, by a longer straight vertical bar, F, the latter being midway between the side bars, A, and being connected thereto by short curved or arched cross-bars G.

I claim—

1. The design for the leg or side frame of a sewing-machine stand herein shown and described, the same consisting of side bars, top and bottom cross-bars, and an oval frame at the lower part of the leg, resting on the lower cross-bar and connected by straight bars with the said side bars and top bar. 45

2. The design for the leg or side frame of a sewing-machine stand herein shown and described, the same consisting of curved side bars, a straight top cross-bar, a doubly-curved bottom cross-bar, and an oval frame at the lower part of the leg, resting on the lower cross-bar and connected by straight bars with the said side bars and top bar. 50

3. The design for the leg or side frame of a sewing-machine stand herein shown and described, the same consisting of the curved side bars, A, the straight top cross-bar, B, the curved bottom cross-bar, C, the oval frame D, the straight cross-bar E, the straight central bar F, and the curved cross-bars G. 65

In testimony whereof I affix my signature in presence of two witnesses.

LEBBEUS B. MILLER.
